UNITED STATES PATENT OFFICE

CHARLES S. ACKLEY, OF BROOKLYN, NEW YORK, ASSIGNOR TO ACKLEY HOLDING CORPORATION, OF NEW YORK, N. Y., A CORPORATION OF NEW YORK

APPARATUS FOR PLACING WAVES IN HAIR

Application filed July 26, 1929. Serial No. 381,189.

This invention relates to apparatus for placing waves in hair.

Various forms of heating devices or rods have been devised for placing waves in hair.

5 In order to produce a lasting wave, the hair must be wound very tightly around the heating rod or tube and must be securely held thereon.

In carrying out the usual method of so called "permanent" waving, a plurality of strands of hair are first tied together close to the scalp. The tied strands are then secured to one end of the curling or heating tube or rod by tying the grouped strands thereto 15 and the strands are then wound tightly around the rod and the ends are tied to the rod. A moistened strip of felt or absorbent material, such as a pad, is then wound around the hair and this material is usually tied.

20 It will be evident that the carrying out of the method just outlined requires a considerable amount of time and when it is considered that the operation outlined must be repeated for thirty or forty different groups 25 of strands on one head, the time expenditure is exceedingly great.

This invention has for its salient object to provide a device of the character specified, so constructed and arranged that its use will 30 cut down very materially and to a minimum, the time required to produce or place waves in hair.

Further objects of the invention will appear from the following specification taken 35 in connection with the drawings, which form a part of this application, and in which

Fig. 1 is an elevational view, partly in section, of a hair waving device constructed in accordance with the invention;

40 Fig. 2 is a transverse sectional elevation taken substantially on line 2-2 of Fig. 1;

Fig. 3 is an elevational view of a portion of the clip device, namely, the ring which is slidably and non-rotatably mounted on the 45 tubular member or sheath on which the hair is wound;

Fig. 4 is an elevational view of the spring which is placed around the ring;

50 Fig. 5 is a sectional elevation of the outer ring on which the clip members are mounted;

Fig. 6 is a sectional elevation illustrating a modified form of sheath; and

Fig. 7 is a view similar to Fig. 3 but showing a ring adapted for use with the sheath construction shown in Fig. 6.

The invention briefly described consists of an improvement on the construction covered in Patent No. 1,652,751, granted December 13, 1927, to Ackley. In the patent referred to, there is shown a clip which is slidably mounted on the sheath but is non-rotatable with respect thereto. The invention covered in this application consists of a clip which is slidably mounted on the sheath and is rotatable in one direction only. The sheath may be heated in any suitable manner and the hair is secured to the sheath at one end thereof and close to the scalp by means of a clip. The hair is then wound tightly around the sheath and the free end is placed under the 55 clips carried by a slidably mounted member. This member, with the clips, is rotatable in one direction and tightly secures the hair to the sheath, the hair being wound around the rod or tube to the end of the strand. With 60 this device, therefore, no straight tip or end 65 will be left, but the entire length will be 70 waved.

Further details of the invention will appear from the following description.

80 In the particular embodiment of the invention illustrated, the hair is wound on a perforated sheath 20 which may be heated in any suitable manner. In the drawings there is shown a heating element comprising 85 a tube 25 having a high resistance wire 26 therein, the ends of which are connected to terminals 27 and 28 carried by a plug 29 disposed at one end of the sheath 20. The tube 25 is preferably provided on its outer 90 surface with a covering 30 of absorbent material. The covering 30 is preferably spaced to a slight extent from the inner surface of the sheath 20.

The sheath 20 is non-circular in outline, 95 being shown in Fig. 2 as elliptical.

A plug 35 is secured to the outer end of the sheath and a cork tip or button 36 is connected to the plug 35 and extends beyond the plug for the purpose of insulating the 100

sheath from the scalp of the person receiving the wave. A clip 37 is mounted on the plug 35 and is adapted to secure the strand of hair near the scalp.

In order to secure the other end of the strand of hair, a clip slidably mounted on the sheath 20. This clip comprises an inner ring 40 which conforms in cross section to the cross section of the outer surface of the sheath and since the sheath is non-circular in cross section, the ring is non-rotatable but is slidably mounted thereon. The outer surface of the ring 40 has a notch 41 therein, in which there is positioned an offset end or flange 42 of a spring 43. The spring 43 is formed from flat stock and is wound into the shape shown in Fig. 4 and thus extends around the ring once and a fraction times. As shown, the spring extends around the ring slightly more than one and one-quarter revolutions. A ring 45, which is shown in Fig. 5, is placed over the ring 40 and spring 43 and has a flange 46 which extends inwardly and encloses one edge of the ring and spring. Clips 46' are secured to the outer surface of the ring 45 and are bent inwardly as shown at 47 and longitudinally of the sheath as shown at 48. The clips are formed of resilient material and are adapted to resiliently clamp or hold the free end of the strand of hair.

In operation, after the hair has been wound tightly around the sheath 20, the clip device is moved longitudinally on the sheath until the clips engage the free end of the hair. The outer ring and the clips carried thereby are then turned or rotated on the inner ring and spring in the direction in which the hair is wound on the sheath, thus tightening the coil of hair on the sheath and causing the entire length of the strand to be wound on the rod or sheath. The spring 43 effectively prevents any rotation of the outer ring in the reverse direction since rotation in such a direction tends to cause the spring to unwind or, in other words, tends to force the spring outwardly against the inner surface of the ring 45.

In Fig. 6 there is shown a sheath 50 which is formed of sheet material, the ends of which are clinched together, as shown at 51, thus forming a longitudinal ridge on the sheath. When this form of sheath is used, the ring 40 will be provided with a recess 52, as shown in Fig. 7, to receive the ridge 51. Although the drawings show the hair wound on a tubular member or sheath and the clip device mounted on the sheath, the device could be used with a rod on which the hair is wound. In such case the rod would be irregular or non-circular in section and the inner ring of the clip device would be corresponding in section.

From the foregoing description it will be clear that a simple, practical and efficient clip device has been provided for aiding in

tightly securing a coil of hair on a sheath and for preventing the unwinding or loosening of the coil during the operation of the apparatus.

Although one specific embodiment of the invention has been particularly shown and described, it will be understood that the invention is capable of modification and that changes in the construction and in the arrangement of the various cooperating parts may be made without departing from the spirit or scope of the invention, as expressed in the following claims.

What I claim is:

1. A hair waving device comprising an elongated member adapted to receive the hair, an element slidably mounted on said member, a clip mounted on said element and rotatable in one direction only thereon, and means for holding the clip against rotation in the opposite direction. 80

2. A hair waving device comprising an elongated member, an element slidably mounted on said elongated member, said member and element having coating means for preventing rotation of the element on said member, and a clip mounted on said element and rotatable in one direction only thereon. 90

3. A hair waving device comprising an elongated tubular member, a member slidably mounted thereon, a ring mounted in said slideable member and rotatable in one direction only thereon, and hair clamping means carried by said ring. 95

4. A hair waving device comprising an elongated tubular member, a member slidably mounted thereon, a ring mounted on said slideable member and rotatable in one direction only thereon, and resilient hair clamping means carried by said ring. 100

5. A hair waving device comprising an elongated tubular member, a member slidably mounted thereon, a ring mounted on said slideable member and rotatable in one direction only thereon, and hair clamping means carried by said ring and extending longitudinally of the tubular member. 110

6. A hair waving device comprising an elongated tubular member, a member slidably mounted thereon, a ring mounted on said slideable member and rotatable in one direction only thereon, and resilient hair clamping means carried by said ring and extending longitudinally of the tubular member. 115

7. A hair waving device comprising an elongated tubular member, a member slidably mounted thereon, a ring mounted on said slideable member and rotatable in one direction only thereon, and a plurality of hair clamping means carried by said ring. 120

8. A hair waving device comprising an elongated sheath having a non-circular cross section, a member slidably mounted thereon and having inside dimensions adapted to slidably and non-rotatably fit the outer sur- 130

face of said sheath, and a clip device mounted on said member and rotatable in one direction only thereon.

9. A hair waving device comprising a sheath, a member slidably and non-rotatably mounted thereon, a spring surrounding said member, one end of the spring being connected to said member and the other end being free, a ring surrounding said spring and contacting therewith, and a clip carried by said ring.

10. A hair waving device comprising a sheath, a member slidably and non-rotatably mounted thereon, a spring surrounding said member, one end of the spring being connected to said member and the other end being free, a ring surrounding said spring and contacting therewith, and a clip carried by said ring and extending to a position adjacent said sheath.

11. A hair waving device comprising a sheath, a member slidably and non-rotatably mounted thereon, a spring surrounding said member, one end of the spring being connected to said member and the other end being free and overlapping the first named end, a ring surrounding said spring and contacting therewith, and a clip carried by said ring.

12. A hair waving device comprising a sheath, a member slidably and non-rotatably mounted thereon, a ring surrounding said member, friction means between said ring and member constructed and arranged to permit the rotation of the ring on the member in one direction only, and a clip carried by said ring.

13. A hair waving device comprising a sheath, a member slidably and non-rotatably mounted thereon, a ring surrounding said member, friction means between said ring and member constructed and arranged to permit the rotation of the ring on the member in one direction only, and a plurality of clips carried by said ring.
